C. Bushman,

Skate,

No 61,998.

Patented Feb. 12, 1867.

United States Patent Office.

CHARLES BUSHMAN, OF WEST CHESTER, PENNSYLVANIA.

Letters Patent No. 61,998, dated February 12, 1867.

IMPROVEMENT IN SKATES.

The Schedule referred to in these Letters Patent and making part of the same.

TO ALL WHOM IT MAY CONCERN:

Be it known that I, CHARLES BUSHMAN, of West Chester, in the county of Chester, and State of Pennsylvania, have invented certain new and useful improvements in Skates, and that the following is a full, clear, and exact description of the same, reference being had to the accompanying drawings, making a part of this specification, in which—

Figure 1 represents a top plan of the skate.

Figure 2 represents a side view of the same as it appears when fastened to the foot, shoe, or boot.

Figure 3 represents a view of the under side of the heel of the shoe or boot showing the device for fastening the heel part of the skate thereto.

Figure 4 represents a section through the heel of the boot or shoe and skate, to show the device for holding the two parts together.

Similar letters of reference, where they occur in the separate figures, denote like parts of the skate in all the drawings.

My invention consists, first, in the double bends, curls, or springs at each end of, and as prolongations of, the runner of the skate, so that any ordinary weight on the skate will cause the curls or springs to yield only at the extreme ends, and any excessive weight or jar bring the inner ends of the curls or springs into action, and thus relieve the skater from any jar without impeding his motion on rough ice. And my invention further consists in placing a plate with an elliptical hole in it on the heel part of the skate, and a screw or stud, with an elliptical head, in the heel of the boot or shoe, for the purpose of uniting that part of the skate to said boot or shoe, so that any one using the skate may readily apply to the heel of the boot or shoe the screw or stud for forming a part of the fastening at that point, the other part being made as a part of the skate by the manufacturer thereof.

To enable others skilled in the art to make and use my invention, I will proceed to describe the same with reference to the drawings.

The skate-runner A is made of the form shown in the drawing, fig. 2. At its heel portion it rises in a vertical or arched direction, as shown at a, and is then bent over into a horizontal, or nearly so, position, as at b, and the end bent around into a curl, as at c, the lower bend of said curl approaching very near to the top of the runner. The forward part of the runner is curved upward and backward, as at d, thence it extends rearward, as at e, and slightly bent downward or concave to suit the ball of the foot or boot, and then curled around, as at f, the lower part of the curl being a short distance above the top of the runner. The object of the bends and curls in the prolonged portions of the runner is, that with the ordinary weight of the skater the spring or yield shall be at the points 1 and 2. But when running over rough ice there is an additional yielding or springing motion at the points 3 and 4, and thus the skater glides easily over rough ice without any jar or being impeded in his progress thereby. On the horizontal or slightly curved portions b e of the skate are fastened, respectively, the heel plate B and the sole plate C for supporting the rear and front of the foot, boot, or shoe; and to these plates are fastened the straps g h i, the one, g, for going up over the instep, and those, h i, for passing over the forward part of the foot, where they are fastened by buckles in the usual way. On the front or sole plate C there are adjustable side pieces D, with turned-up ends j for catching and holding the foot, to prevent it or the skate from moving laterally. These side pieces are made adjustable by means of the slots k and set-screws l in the usual well-known ways.

Heretofore it has been common to put an elliptically-shaped or headed stud on the skate at the heel, which was designed to pass through a similarly shaped hole in a plate fastened to the heel of the boot or shoe; but without such a plate the fastening was useless, and it could not be procured or put on by any one but a mechanic having the proper tools and skill to use them. I obviate all this difficulty by my plan of making and using this heel fastening and support. And I do not simply change these male and female fastenings from the skate to the boot, or *vice versa*, but by a simple construction of one part of the fastening, and that part united to and made a permanent part of the skate, I make it within the capability of any one, though not a mechanic, and with only such instruments as can always be found, to prepare the heel of any boot or shoe, with very little trouble, so that it will unite with the socket or plate on the skate as follows: on the heel plate b there is a raised circular socket, m, having an elliptically-shaped hole, n, in its top, the long diameter of the ellipse run-

ning longitudinally of the skate. This socket is made permanently fastened to the skate, and no detached piece, which is always liable to be lost or mislaid, need go with the skate to form the other part of the fastening. To prepare the heel of any boot or shoe so that it will unite with this socket it is only necessary to bore a round hole, *o*, (see fig. 3, where *E* may represent the heel of a boot or shoe,) and to take an ordinary wood screw and file away on opposite sides of its head so as to give said head an oblong appearance, as at *p*, and to run said screw centrally into the hole *o* until its head is flush with the face of the heel, leaving the long diameter of the head crosswise of the heel, or at right angles to the long diameter of the elliptical hole *n*. The hole *o* in the heel is made to take in the socket *m*, and the hole *n* in the socket is made to take in the head *p* of the screw, when the skate is at right angles to the position it has when properly placed on the boot or shoe. Then by turning the skate a quarter round the diameter of the screw-head and elliptical hole are reversed, the long diameter of one fitting against the short diameter of the other, and so making a firm connection between the boot or shoe and skate.

Having thus fully described my invention, I would state that I do not claim bends or bows at the toe and heel portions of a skate, nor do I claim the application of springs independent of those made by a continuation of the runner itself, these having been used.

But what I do claim as my invention, and desire to secure by Letters Patent, is—

The curls *e f*, formed out of the same piece as the runner, and arranged with regard to the heel and toe plate, and the runner, as herein described and represented.

I also claim a raised circular socket *m*, on the heel plate of the skate, and furnished with an elliptically-shaped hole, *n*, in its top, so that a screw-head slightly filed away on its opposite sides and set in the heel of a boot or shoe may enter and turn in said socket to form a fastening between the heel of the boot or shoe and the skate, as herein described and represented.
